UNITED STATES PATENT OFFICE

CHARLES FOTI, OF ARNOLD, PENNSYLVANIA, ASSIGNOR OF ONE-SEVENTH TO ANTONIO SAULLE, ONE-SEVENTH TO MENOTTI GUIDICE, BOTH OF ARNOLD, PENNSYLVANIA, ONE-SEVENTH TO SALVATORE TAMBURG, ONE-SEVENTH TO FRANK MANGONE, BOTH OF NEW KENSINGTON, PENNSYLVANIA, ONE-SEVENTH TO DOMINICK VERTERAMO AND ONE-SEVENTH TO FERDINANDO GATTO, BOTH OF ARNOLD, PENNSYLVANIA

PEN HOLDING DEVICE FOR INKWELLS

Application filed November 19, 1930. Serial No. 496,731.

This invention relates to inkwells and has for an object the provision of a well into which the point of a pen may be conveniently dipped, and which will support the holder 5 of the pen with the point submerged, and thus prevent corrosion of the point, while the pen will be at all times in convenient position for use.

Another object of the invention is the provision of means for supporting the pen so as to prevent the holder from reaching the ink, whereby the fingers of the user will not become soiled from an inky pen holder.

Another object of the invention is the provision of an inkwell, which in addition to the above and other advantageous features, may have the pen dips and pen supporting means made integral with the inkwell, or they may be separately made.

With the above and other objects in view, the invention further includes the following novel features and details of construction, to be hereinafter more fully described, illustrated in the accompanying drawing and 25 pointed out in the appended claim.

In the drawing:—

Figure 1 is an elevation partly broken away and shown in section and illustrating the use of the invention.

Figure 2 is a top plan view.

Figure 3 is a similar view showing a slightly different form of the invention.

Figure 4 is a section on the line 4—4 of Figure 3.

Referring to the drawing in detail and especially to Figures 1 and 2, the reference character 10 indicates the body of an inkwell which is preferably made of glass or other suitable transparent material. The well is 40 provided with an integral top 11 which is slightly spaced inward from the upper edge of the side walls of the body, and which is provided with a plurality of openings 12 of suitable size and shape and defining pen dips.

The top 11 is relatively thick so that the ink 13 within the well may extend into the openings 12 to be conveniently reached by the point of a pen. The openings 12 are relatively small so that the pen holder, when the

point is submerged, will rest upon the top of the well 11 adjacent the openings and will thus be prevented from coming in contact with the ink. This will prevent the hands of the user of the pen from becoming soiled from this cause.

In Figures 3 and 4 of the drawing, the body 14 of the inkwell is preferably made of glass or other transparent material and is provided in its top with an opening 15. The 60 walls of the opening taper downwardly and inwardly and are adapted to be engaged by the tapered edge of a removable closure 16. If desired an inwardly extending flange 17 may extend around the bottom of the opening 65 to provide a seat for the closure 16.

The closure 16 may be made of glass, metal, or any other suitable material and is provided with a plurality of openings 18, forming pen dips after the manner of the openings 12.

The closure 16 is provided with a finger piece 19 for convenience in removing and replacing the closure. The advantages of this form of the invention are the same as in the preceding form, except that the closure 16 may be made and sold separately for use in connection with inkwells having openings in the top whose walls are tapered.

The invention is susceptible of various 80 changes in its form, proportions and minor details of construction and the right is herein reserved to make such changes as properly fall within the scope of the appended claim.

Having described the invention what is 85 claimed is:—

An inkwell comprising a body having a top provided with a plurality of concentrically arranged circular series of openings of various shapes to receive the writing end of a pen, 90 said openings having vertical walls and being of a size whereby the portions of the top about the same provide pen holder engaging shoulders to support a holder in a substantially upright position, and the top being relatively 95 thick so that ink within the body may extend into the openings a sufficient distance to surround the writing end of the pen.

In testimony whereof I affix my signature.

CHARLES FOTI. 100
